UNITED STATES PATENT OFFICE

100,283

DESIGN FOR A FOOTBALL MITT

Ralph D. Ovenden, Sutton, Nebr., assignor of one-fourth to Harry J. Rothrock, Sutton, Nebr.

Application October 30, 1935, Serial No. 59,279

Term of patent 7 years

To all whom it may concern:

Be it known that I, Ralph D. Ovenden, a citizen of the United States, residing at Sutton, in the county of Clay and State of Nebraska, have invented a new, original, and ornamental Design for a Football Mitt, of which the following is a specification, reference being had to the accompanying drawing, forming part thereof.

The form of the football mitt is in fanciful simulation of a football, contrasting colors being employed as shown.

I claim:

The ornamental design for a football mitt, as shown and described.

RALPH D. OVENDEN.
